ROOF-HOOD FOR A VENTILATION TWIN-DUCT

Jorgen Holt, Naestved, Christian Videmark, Haslev, and
Palle Hein Christiansen, Naestved, Denmark, assignors
to Nordisk Ventilator Co. Aktieselskab, Naestved,
Denmark

Filed Dec. 8, 1972, Ser. No. 313,419

Claims priority, application Denmark June 9, 1972

Term of patent 14 years

Int. Cl. D23—04

U.S. Cl. D23—163

FIG.1

FIG.2

FIG.3

FIG. 1 is a top perspective view of a roof-hood for a ventilation twin duct showing our new design;

FIG. 2 is a bottom perspective view thereof;

FIG. 3 is a sectional view taken along an axial plane of the roof-hood.

We claim:

The ornamental design for a roof-hood for a ventilation twin-duct, as shown and described.
